UNITED STATES PATENT OFFICE

WALTER HOLMS, OF CLEVELAND, OHIO, ASSIGNOR TO THE CLEVELAND FOLDING MACHINE COMPANY, OF CLEVELAND, OHIO, A CORPORATION OF OHIO

PAPER HANDLING MACHINE

Application filed August 13, 1928. Serial No. 299,278.

This invention relates to improvements in paper handling machines, and has reference particularly to means for diverting two or more different sheets or signatures following each other through a folding machine or other paper handling machine into two or more different courses where they may be collected separately.

Sheet deflector mechanism for the purpose stated has been suggested heretofore but in such mechanism, so far as I am aware, the deflector has oscillated back and forth between its different operative positions. In the present invention the deflector turns always in the same direction and is preferably power driven through a friction clutch which slips whenever the deflector is motionless, and becomes effective to turn the deflector whenever a stop mechanism that is provided in the machine is withdrawn by means which are actuated by the travel of the sheets themselves. The deflector operating mechanism therefore is not synchronized with the other moving parts of the machine, but is operated in properly timed relation with the travel of the sheets, being motionless when the travel of the sheets is interrupted for any reason.

One of the objects of the invention is the provision of a power means for turning the deflector, so that the load imposed upon the folded sheets is only sufficient to trip a stop mechanism. This is of some importance where light weight material is to be handled.

Another object is the provision of simple and effective stop mechanism, preferably engaging the deflector directly, to hold the same in any one of a plurality of operative positions.

Other objects and features of novelty will appear as I proceed with a description of that embodiment of the invention which, for the purposes of the present application, I have illustrated in the accompanying drawings, in which:

45 Figure 1 is a fragmental side elevational

view of a machine embodying the invention, shown in operative relation with the delivery end of a folding machine or the like.

Fig. 2 is a horizontal sectional view taken substantially on the line 2—2, Fig. 1.

50 Fig. 3 is a horizontal detail sectional view taken substantially on the line 3—3, Fig. 1.

Fig. 4 is a vertical section of a friction clutch which may be employed in connection with the invention, the section being taken 55 on the line 4—4 of Fig. 3; and

50 Figs. 5 and 6 are vertical sectional views taken substantially on the line 5—6, Fig. 2, showing the movable deflector in two different operative positions, the next succeeding 60 position of the stop mechanism in each case being shown in dotted lines.

65 In the drawings I have shown at 10 a fragment at the delivery end of a folding machine or the like, comprising sheet forwarding means consisting of rolls 11 and 12, which carry intermeshing gears 13 and 14 respectively, the gear 13 being driven by suitable means through driving connections from the motor of the machine (not shown).

70 The machine of the present invention includes a frame 15, which is adapted to be set up closely adjacent to the delivery end of the folding machine, as indicated in Figs. 1, 5 and 6, and is preferably detachably secured thereto. The frame 15 carries a guide plate 16 which is positioned to receive the sheets delivered from the sheet forwarding means 11, 12 and to direct them into feed rolls 17,

75 18. The latter rolls have intermeshing gears 19, 20, which may and preferably do derive their power from the folding machine, as through an idler 21, the gears 19, 20 turning at the same speed as the gears 13, 14, so that the two pairs of feed rolls to which they are connected shall turn at the same rate of speed.

80 On the rear side of the machine the roll 17 carries a gear 22 which meshes with an idler 23, the idler in turn meshing with a gear 24 which is mounted on shaft 25 that 85

extends across the machine and carries paper feeding wheels 26. Below the shaft 25 there are two feed rolls 28, 29 of metal or other non-resilient material that are driven through 5 gears 30, 31 (Fig. 1). The gear 31 in turn meshes with a gear 32 on shaft 33 which carries paper feeding wheels 34 similar to the wheels 26 on the shaft 25. As indicated in Figs. 5 and 6, sheets may travel either between 10 the roll 28 and the wheels 26 or between the roll 29 and the wheels 34, that is to say, either in an upper course or in a lower course. Those sheets which take the upper course are deposited upon a suitable collecting means, 15 as for instance a stacker belt 35, while those taking the lower course may be deposited upon a stacker belt 36. These belts may be driven by any suitable means, as for instance by a series of gears 37, 38, 39 at the back of 20 the machine the gear 37 being driven from gear 30 through a reduction gearing consisting of a pair of idlers 9 and 99 secured together, idler 9 meshing with gear 30 and idler 99 meshing with gear 37.

25 A paper deflector 41 is mounted in the frame on the rear side of the feed rolls 17, 18, being rotatable upon a trunnion 42 at its rear end and at its forward end being pinned to a stub shaft 43 which extends through a bearing in the frame 15, as well shown in Fig. 3. A gear 44 is loosely mounted upon the shaft 43 and is driven continuously in a clockwise direction, as viewed in Fig. 1, by a gear 40 on the forward end of roll 29. Clutch blocks 30 35 45, 46, lined with friction material engage the shaft 43 adjacent the gear 44, being resiliently clamped upon the shaft by bolts 47 acting through coil springs 48. One of the blocks 45, 46 is pinned to the hub of gear 44, 40 so that these blocks move with the gear at all times. Hence there is a tendency for the shaft 43 to turn with the clutch blocks 45, 46 in a clockwise direction, but when its rotation is interfered with the clutch blocks turn 45 upon the shaft.

Referring now to the stop mechanism, in connection with shafts 25 and 33 I employ pivoted shoes 49 and 50 respectively, which are mounted upon the inner ends of short rock 50 shafts 51 and 52, the outer ends of which extend through bearings in the forward wall of the machine. These shoes should just clear the rolls 28 and 29, so that when a sheet passes 55 between one of these rolls and the adjacent shoe, the shoe will be swung to rotate the shaft 51 or 52 as the case may be. Obviously it is necessary to adjust the distance between the shoes and the rolls 28, 29 in order to enable them to function properly for different 60 weights of paper and different numbers of folds in the sheets handled, and to this end the inner bearings for the shafts 51, 52 are mounted in levers 53, 54, which are pivotally mounted intermediate their ends upon pins 65 55 and 56 that are threaded into brackets 57

and 58 which are bolted to the frame. The ends of the levers 53 and 54 remote from the shaft bearings are adjustable by means of screws 59 and 60 which may be held in adjusted position by lock nuts 61 and 62 respectively, the levers being held against the ends of the screws by coil springs 63, 64 which have bearing upon the levers and upon fixed abutments in the brackets 57 and 58.

70 Inasmuch as the adjustment just described moves the inner bearings of the shafts 51 and 52 while the outer bearings thereof are fixed within the frame of the machine, I form each of these shafts with curved surfaces, as illustrated in Fig. 2, where the shafts engage their bearings. The shoes 49, 50, their adjustable mounting, and the details of the shafts 51, 52 form no part of my invention, except in combination with certain other parts of the machine herein described.

75 On the outer ends of the shafts 51 and 52, outside the frame of the machine, there are short cranks 65 and 66 connected by links 67 and 68 with cranks 69 and 70 which are fixed to shafts 71 and 72, the latter being oscillatably mounted in and extending through the frame 15. The shaft 71 on its inner end carries a finger 73 with a hook on the free extremity thereof. The shaft 72 on its inner end carries a similar finger 74 which, however, 90 has a plain extremity. The hooked end of the finger 73 forms a stop to hold the deflector 41 in the position illustrated in Fig. 5, while the free extremity of finger 74 constitutes a stop to hold the deflector in the position of Fig. 6. In order to urge the fingers 95 73 and 74 to their operative positions, shown in full lines in Figs. 5 and 6, and also in order to urge the shoes 49 and 50 toward the left in those figures, I attach to the outer end of crank 65 and to a lug on link 68, tension springs 75 and 76 respectively, which at their outer ends are connected with screws 77 and 78 threaded through pins 79 and 80 fixed in the frame of the machine. By this means the 100 tension of the springs 75, 76 may be regulated.

105 Operation: Assuming that folded sheets or signature of two different kinds are following each other in regular sequence through a folding machine or the like having sheet forwarding means 11, 12, and that as the first sheet travels into the machine and through the feeding rolls 17, 18 the deflector 41 is in the position of Fig. 5, this sheet will be divided by the deflector upwardly between roll 28 and the wheels 26 of shaft 25. After the forward edge of the sheet in passing over the roll 28 strikes the shoe 49, the latter is swung to the dotted line position of 115 Fig. 5, and this movement of the shoe is transmitted through its shaft 51, the crank 65 thereon, the link 67, crank 69, and shaft 71 to stop finger 73, throwing the latter to the dotted line position of that figure.

Immediately the rotating friction clutch blocks 45, 46 grip the shaft 43 and turn the same clockwise, whereby the deflector is swung through something less than a right angle to the position of Fig. 6, where its movement is interrupted by the stop finger 74. This operation may, and frequently does, occur before the rear edge of the sheet has passed entirely over the deflector, but the movement of the deflector before the travel of the rear edge of the sheet thereover does no harm since the sheet is firmly gripped by roll 28 and wheels 26. Furthermore the deflector is always in position to properly direct the next succeeding sheet, no matter how closely it follows.

The next succeeding sheet now strikes the under side of the deflector 41 and is directed downwardly between the roll 29 and the wheels 34 on shaft 33, whereupon the shoe 50 is swung to dotted line position and operates through shaft 52, crank 66, link 68, crank 70, and shaft 72 to throw stop finger 74 to the dotted line position of Fig. 6, thereby releasing deflector 41. The friction clutch again takes effect and turns shaft 43, this time through an angle somewhat greater than ninety degrees, to a position one hundred and eighty degrees from the first position of Fig. 5, where its motion is interrupted by the hook on stop finger 73.

The cycle of operations then repeats itself, the sheets of one kind passing over the upper course and being collected on the stacker belt 35, while the sheets of the other kind pass over the lower course and are collected on stacker belt 36.

While I have illustrated a deflector having but two sides, it will be apparent that one having three or more sides might be substituted, each edge between the sides engaging one finger stop and then the other. The number of courses also is not necessarily limited to two, although a machine having two courses is illustrated herein for the sake of simplicity in the disclosure of the invention. Still other changes from the disclosed structure are possible without departing from the spirit of the invention, and I therefore desire it to be understood that the invention is not to be construed as limited by any of the details included in the drawings or specification.

Having thus described my invention, I claim:

1. In a paper handling machine, means for directing sheets into different courses comprising a rotatably mounted deflector, power means tending to rotate said deflector in a given direction, means adapted to hold said deflector in any one of a plurality of angular positions, and mechanism actuated by the travel of the sheets themselves for operating said last named means to permit said deflector to advance under the influence

of said power means from one angular position to another angular position.

2. In a paper handling machine, means for directing sheets into different courses comprising a rotatably mounted deflector, power means tending to rotate said deflector in a given direction, a plurality of stops adapted to hold said deflector in any one of a plurality of angular positions, and mechanism actuated by the travel of the sheets themselves for withdrawing said stops one at a time momentarily.

3. In a paper handling machine, sheet forwarding means, and means for directing sheets from said forwarding means into different courses, said last-named means comprising a pivoted shoe adapted to be swung upon its pivot by the travel of the sheet, a rotatably mounted sheet deflector, power means tending to rotate said deflector in a given direction, and a stop operatively connected to said shoe for movement thereby, said stop being adapted when in one position to hold said deflector against rotation, and a second stop adapted to be engaged by said deflector when released by said first named stop.

4. In a paper handling machine, sheet forwarding means, and means for directing sheets from said forwarding means into different courses, comprising a rotatably mounted deflector having a plurality of edges parallel to the axis of rotation, and means adapted to be set in motion by the travel of a sheet for rotating said deflector intermittently through a portion of a revolution to present a different angular position of the deflector to the next sheet advancing from said sheet forwarding means.

5. In a paper handling machine, sheet forwarding means, and means for directing sheets from said forwarding means into different courses, said last-named means comprising a rotatably mounted deflector having a plurality of edges parallel to its axis of rotation, power means tending to rotate said deflector in a given direction, and means actuated by the travel of the sheets themselves for making said power means effective intermittently to rotate said deflector through a portion of a revolution whereby a different angular position of the deflector is presented to the next sheet advancing from said sheet forwarding means.

6. In a paper handling machine, sheet forwarding means, and means for directing sheets from said forwarding means into different courses, said last-named means comprising a rotatably mounted deflector having a plurality of edges parallel to its axis of rotation, power means tending to rotate said deflector in a given direction, a pair of stops, one of which is adapted to hold said deflector with any one of its edges on one side of the line of travel of sheets from said

forwarding means, and the other of which is adapted to hold said deflector with any one of its edges on the other side of the line of travel of the sheets from said forwarding means, and means adapted to be set in motion by the travel of the sheets themselves for withdrawing momentarily first one and then the other of said stops.

7. In a paper handling machine, sheet forwarding means, and means for directing sheets from said forwarding means into either one of two different courses, said last-named means comprising a rotatably mounted deflector having a plurality of edges parallel to its axis of rotation, power means tending to rotate said deflector in a given direction, a stop adapted to hold said deflector with any one of its edges on one side of the line of travel of sheets from said forwarding means, a second stop adapted to hold said deflector with any one of its edges on the other side of the line of travel of sheets from said forwarding means, and means located in each of said courses and adapted to be set in motion by the travel of the sheets therethrough for moving said stops momentarily out of operative position.

8. In a paper handling machine, sheet forwarding means, a movable deflector for directing sheets from said forwarding means into either one of two different courses, and means associated with each of said courses and adapted to be set in motion by the travel of a sheet therealong for moving said deflector to direct a succeeding sheet into the other course, said two last-named means being independent of each other.

9. In a paper handling machine, means for causing sheets to travel in a given path, means for directing sheets from said path into different courses comprising a rotatably mounted deflector, the edges of which are movable across said path, power means tending to rotate said deflector in a given direction, a plurality of stops each adapted to hold said deflector in position to direct a sheet into one of said courses, and mechanism adapted to be set in motion by the travel of a sheet in a given course for withdrawing the corresponding stop momentarily, whereby said deflector turns into position to direct the next succeeding sheet into a different course, said movement of the deflector being completed before the rear end of the first sheet passes said deflector.

10. In a paper handling machine, means for causing sheets to travel in a given path, means for directing sheets from said path into different courses comprising a rotatably mounted deflector, the edges of which are movable across said path, power means tending to rotate said deflector in a given direction, a plurality of stops each adapted to hold said deflector in position to direct a sheet into one of said courses, and mechanism

adapted to be set in motion by the travel of the forward edge of a sheet in a given course for withdrawing the corresponding stop momentarily, whereby said deflector turns into position to direct the next succeeding sheet into a different course, said movement of the deflector being completed before the rear edge of the first sheet passes the said deflector.

In testimony whereof, I hereunto affix my signature.

WALTER HOLMS.
